DISPLAY BLISTER FOR A PACKAGE OF BOWS
AND RIBBON OR THE LIKE

Maurice C. Robinson, 16 Shornecliffe, Montreal,
Quebec, Canada

Filed Apr. 27, 1959, Ser. No. 55,682

Term of patent 14 years

(Cl. D58—2)

Figure 1 is a front perspective view of a display blister for a package of bows and ribbon or the like, embodying my new design; and

I claim:

The ornamental design for a display blister for a package of bows and ribbon or the like, as shown.
